UNITED STATES PATENT OFFICE

NORMAN B. GEDDES, OF NEW YORK, N. Y.

DESIGN FOR A RADIOCABINET

Application filed August 15, 1931. Serial No. 40,861. Term of patent 7 years.

To all whom it may concern:

Be it known that I, NORMAN B. GEDDES, a citizen of the United States, residing in New York, county of New York, New York, have invented a new, original, and ornamental Design for Radio Cabinet, of which the following is a specification, reference being had to the accompanying drawing, forming part thereof, in which the figure is a perspective

view of a radio cabinet made in accordance with my invention. The opposite side of the cabinet is identical with that shown, while the rear side corresponds to the front with the exception that the central grille is lacking.

I claim:

The ornamental design for a radio cabinet, as shown and described.

NORMAN B. GEDDES.
